SPOON REST

Peter F. Murray, Montebello, Calif.

Application July 8, 1950, Serial No. 11,023

Term of patent 7 years

(Cl. D44—24)

To all whom it may concern:

Be it known that I, Peter F. Murray, a citizen of the United States of America, residing at Montebello, county of Los Angeles, State of California, have invented a new, original, and ornamental Design for Spoon Rests, of which the following is a specification, reference being had to the accompanying drawing, forming a part hereof.

Fig. 1 is a top plan view of a spoon rest embodying my new design;

Fig. 2 is a side elevational view;

Fig. 3 is an end elevational view; and

Fig. 4 is a cross-sectional view thereof, taken on the line 4—4 of Fig. 1.

I claim:

The ornamental design for a spoon rest, as shown.

PETER F. MURRAY.
